United States Patent Office.

JOHN A. QUICK, OF SOUTH DANVILLE, NEW YORK.

Letters Patent No. 89,791, dated May 4, 1869.

IMPROVEMENT IN CULTIVATORS.

The Schedule referred to in these Letters Patent and making part of the same.

To all whom it may concern:

Be it known that I, JOHN A. QUICK, of South Danville, in the county of Steuben, and State of New York, have invented certain new and useful Improvements in Cultivators; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to cultivators, and consists in so constructing and arranging one or more harrows, in connection with the cultivator, that they may be revolved horizontally, in front of the cultivator-teeth, by the revolutions of the wheels of the cultivator.

In the drawings—

Figure 1 is a longitudinal vertical section, and

Figure 2 is a top plan view.

In constructing my cultivator, I attach one of the wheels, A, rigidly to the axle B, and the other, C, loosely.

To the axle B, I connect a frame, D, at its front end, so as to turn easily on the axle, as clearly shown in fig. 2.

The rear end of the frame D, I provide with a cross-piece, a, and to it attach cultivator-teeth, b, and also, in its centre, an upright, c, having a wheel, E, pivoted in its lower end, and also having a slot, e, through which a set-screw, f, passes, so as to admit of a vertical adjustment of the upright c, for the purpose of regulating the depth at which the teeth b shall operate as desired, as clearly shown in fig. 1.

To the axle B, I key a bevel-gear wheel, F, which meshes into a bevel-gear, G, attached to the front end of a horizontal shaft, H, mounted in the cross-pieces g and I of the frame D.

Just in front of the cross-piece I, and on the shaft H, I key a bevel-gear wheel, J, which meshes into a bevel-gear wheel, K, attached to a vertical shaft, L, mounted in the cross-piece I, and a corresponding cross-piece, M, of the frame D, as clearly shown in figs. 1 and 2.

To the lower end of the vertical shaft L, I attach, firmly, a plate or frame, N, provided with any desired number of harrow-teeth, h, suitable for stirring and pulverizing the soil, and arranged so as to work at the same depth with the cultivator-teeth b, if required.

The cross-pieces I and M are located so as to allow the plate or frame N to come a short distance in front of the cultivator-teeth b.

On the vertical shaft L, and between the cross-pieces I and M, and under the bevel-wheel K, I attach a gear-wheel, O, to give motion, if desired, either directly, or through intermediate pinion-wheels i, to gear-wheels j and K, attached to vertical shafts l and m, mounted in the cross-pieces I and M, and on each side of the vertical shaft L, as clearly shown in fig. 2.

These vertical shafts, l and m, have also attached, to their lower ends, frames or plates, provided with harrow-teeth.

To the cross-piece I, I connect, loosely, in any suitable manner, a rod, n, at one end, and its opposite end I link to a lever, o, one end of which is, in like manner, connected to the cross-bar h of the shafts or tongue of the cultivator, as clearly shown in figs. 1 and 2.

On the cross-bar p, or in any other suitable way, I mount a seat, P, and, in like manner, connect a ratchet-bar, q, as clearly shown in the same figures.

In operating my machine, I first adjust the upright c to suit the depth to which I desire the cultivator-teeth b and the harrow-teeth h to work, then mount into the seat P, and drive over the field, when I desire to operate with it.

As the wheel A, which is rigidly attached to the axle B, revolves, it gives motion, through the bevel-gear F and G, to the horizontal shaft H, which, in turn, through the bevel-gear J and K, gives motion to the vertical shaft L, which, at the same time, through the wheels O and i, and j and K, imparts motion to the shafts l and m.

The shafts L, l, and m, being thus revolved, at the same time, cause the horizontal frames attached to their lower ends to revolve, and in different directions, and, in this manner, thoroughly to break up and pulverize the soil in front of the cultivator-teeth, as well as to tear up and root out all weeds, and similar offensive stuff, as desired.

When, for any purpose, I desire to raise the cultivator-teeth, and the horizontally-revolving harrows from the soil, I draw the lever o forward, till the end of the frame is raised, and then catch it into a notch, in the ratchet-bar q.

It is obvious that the harrow-teeth h may be removable, so that others, of a different kind, and suitable for some specific purpose, may be inserted; as, for instance, instead of using simple harrow-teeth, coulters, or cutting-blades, of any desired shape, may be used.

It is also obvious that the vertical shafts, to which the harrows are attached, may be connected to the wheel of the cultivator, which operates them more directly, and by other gearing, or other mechanical devices than those herein described.

It is also obvious, that, if desired, the mechanism used may connect the harrows with both of the wheels of the cultivator.

I am aware that rotating blades, for cutting or digging up the soil, have been used in steam-plows, and, therefore, I do not claim such; but having thus described my invention,

What I claim, is—

A cultivator, having one or more rotary harrows, mounted in a frame, journalled, at its front end, on the axle of the bearing-wheels, said harrows being rotated, by means of shaft H, with bevel-wheels J G, engaging with the bevel-wheel F, on the axle, substantially as shown and described.

JOHN A. QUICK.
